To all whom it may concern:

Be it known that I, WILLIAM L. PANIKOFF, of New Haven, in the county of New Haven and State of Connecticut, have invented and produced a new and original Design for a Badge or Similar Article; and I do hereby declare the following, when taken in connection with the accompanying drawing and the letters of reference marked thereon, to be a full, clear, and exact description of the same, and which said drawing constitutes part of this specification, and represents a perspective view of a badge embodying my design.

My invention relates to a design for a badge or similar article; and the design consists in the configuration and ornamentation of the badge or similar article, as herein shown and described.

As herein shown, the badge A is of irregular shape, in the center of which is a circular bead B. On one side of the circle is the representation

Over the circle is a streamer E, and beneath the circle is a streamer F, represented as folded in the center, the nutmeg, tree, and streamers being in relief. The badge or similar device is used as a pendant, face of a button, pin, belt-clasp, or for other similar purpose.

Having fully described my invention, what I claim is—

The design for a badge or similar article, as herein shown and described.

In testimony whereof I have signed this specification in the presence of two subscribing witnesses.
